UNITED STATES PATENT OFFICE.

WILLIAM W. BIRNSTOCK, OF YORK, PENNSYLVANIA, ASSIGNOR TO YORK MILK MACHINERY COMPANY, OF YORK, PENNSYLVANIA, A CORPORATION OF PENNSYLVANIA.

CRATE-ADVANCING MECHANISM.

Application filed January 2, 1923. Serial No. 610,358.

To all whom it may concern:

Be it known that I, WILLIAM W. BIRNSTOCK, a citizen of the United States, residing at York, in the county of York and 5 State of Pennsylvania, have invented certain new and useful Improvements in Crate-Advancing Mechanism, of which the following is a specification.

The present invention relates to mechanism for feeding or advancing boxes, crates or other articles progressively and by a step-by-step movement, and it is applicable more especially to bottle washing and similar machines, wherein the bottles are contained in crates or boxes and are fed or advanced through the machine in a manner which presents the crates of bottles successively in operative relation with the bottle washing devices or other mechanisms 15 of the machine. The invention pertains particularly to crate-feeding means which embodies crate-engaging dogs carried by reciprocatory feeding members, it providing novel and improved mechanism by 20 which these dogs are set in operative crate-engaging position preparatory to the advancing movement of the crate feeding members, as well as set in inoperative position 25 to clear and pass the crates preparatory to the return movement of the feeding members, both operations, according to the present invention, being performed by the action 30 of a properly timed operating part of the machine, preferably by a cam which is appropriately shaped to perform both of these 35 operations.

To these and other ends, the invention consists in certain improvements and combinations and arrangements of parts, all as 40 will be hereinafter more fully described, the features of novelty being pointed out particularly in the claims at the end of the specification.

In the accompanying drawings:—

45 Figures 1 and 1^a show, in top plan, the delivery and receiving ends respectively of crate feeding mechanism constructed in accordance with the present invention.

50 Figure 2 represents a transverse section on the line 2—2 of Figure 1, and looking toward the right;

55 Figure 3 is a perspective view of the dog setting or reversing mechanism and its actuating cam;

Figure 4 is a side elevation of the crate-feeding means and the cooperating dog setting mechanism, the crate-feeding means being about to commence its return stroke and the dog-setting mechanism being about to set the dogs in inoperative or crate clearing position;

Figure 5 is a view similar to Figure 4, but showing the crate-feeding means as having commenced its return stroke and the dog-setting mechanism in actuated position after 60 setting the dogs in inoperative position;

Figure 6 is a view similar to Figures 4 and 5, but showing the crate-feeding means at the end of its return stroke, the dog-setting mechanism being shown in the full 70 and dotted lines, respectively, in the positions which it occupies prior to reversal of the dogs to set them in operative position and after reversal of the dogs which sets them in operative crate-engaging position; 75

Figure 7 is a detail view of the cam and cam follower which actuate the dog-setting or reversing mechanism, the cam in this figure being shown in the position which it occupies when the crate-feeding means and dog-setting mechanism are in the position 80 represented in Figure 4; and

Figure 8 is a view similar to Figure 7, but showing the cam in the position which it occupies when the crate-feeding means 85 dog-setting mechanism are in the position shown in Figure 5.

Similar parts are designated by the same reference characters in the several views.

The present invention is applicable to 90 machines of various kinds for the purpose of intermittently advancing a series of articles, as for example, bottle crates or boxes. It is particularly applicable to machines 95 for washing and cleaning milk bottles while contained in crates, and in the present instance the invention is shown applied, as an example, to a bottle washing machine of the type disclosed in my Patent No. 1,435,046, granted November 7, 1922, reference being made to that patent for a complete disclosure of a machine of such type. It is to be understood, however, that the invention 100 is not restricted to bottle washing machines of that particular type, and it will also be understood that while the preferred embodiment of the invention is shown in the accompanying drawings, equivalent constructions 105

are contemplated and these will be included within the scope of the claims.

In the present instance, the bottle washing machine to which the invention is shown applied, and which may be constructed substantially as shown and described in my patent above referred to, comprises a base or frame 1 which may support the various mechanisms of the machine, and a housing 2 which may enclose such mechanisms in the machine, and also the crate-feeding mechanism, the machine being of suitable length and being adapted to receive the bottle-containing crates at one end, the right hand end in Figure 1^a, and to discharge or deliver the bottle containing crates at the other end, the left hand end in Figure 1. The bottle washing and cleansing devices may be constructed and arranged substantially as shown and described in said patent.

The crate-feeding means may be similar to that shown and described in said patent, the crates (shown in dotted lines in certain of the figures) being adapted to rest on and to travel longitudinally along a pair of rails 3 which may be mounted on members 4, the latter being mounted on or forming part of the base or main frame 1. The longitudinal members 4 also guide and support for longitudinal reciprocation a pair of crate-advancing bars or members 5, these bars or members being of sufficient length to enable the dogs or crate-engaging devices thereon to operate upon the desired number of crates. The crate-engaging dogs 6 are positively mounted, at 7, on the upper side of the respective reciprocatory bars 5, the bars 5 being located immediately outside of the crate-supporting rails 3, the dogs being pivoted so that they may swing into and out of the path of the crates resting on the rails 3. The dogs on each reciprocatory bar are connected for simultaneous movement by a bar or member 8, this bar being pivotally connected to the outer ends of the respective dogs at the points 9. By this construction, relative longitudinal movement between the bar 8 and the crate-advancing bar 5 will cause the dogs connected thereto to simultaneously swing either outwardly, so as to clear the path of the crates resting on the rails 3, or to swing simultaneously inwardly or into substantially the positions shown in Figures 1 and 1^a, so as to engage the rear sides of a row of crates resting on the rails 3 and to advance this row of crates when the crate-advancing bars 5 are reciprocated in the forward or crate-advancing direction. When the dogs occupy the latter position, the thrust or load imposed upon them by the application of a force sufficient to advance the crates may be sustained by stops 10 on the sides of the dogs which may come

against the outer sides of the respective crate-advancing bars 5. The crates to be advanced are introduced successively or one at a time at the right-hand end (Fig. 1^a) in a position to be picked-up by the pair of dogs 6 on the extreme right-hand ends of the reciprocatory bars 5, and the crates, after passing through the machine, are delivered successively at the left-hand end (Fig. 1), from which point the crates may be removed by hand or by any other suitable means.

The crate-advancing bars 5, during the operation of the machine, are reciprocated preferably by a regular to-and-fro motion obtained from a crank. Any suitable driving means may be employed for the purpose. For example, such driving means in the present instance comprises a rocker arm 10^a which is pivoted at 10^b to a relatively fixed frame, as shown, and is operatively connected by a link 11 to a cross member 12, the latter connecting the pair of crate-advancing bars 5. A cross-head carried by a crank pin 13 operates in the rocker arm, this crank pin being fixed to a gear 13^a which is keyed or otherwise fixed to a shaft 14 and driven by a pinion 14^a which latter is fixed on a shaft 15. The shaft 15 has a gear 15^a fixed thereon which meshes with a pinion 16, the latter being fixed to a gear 16^a and the pinion 16 and gear 16^a being loosely mounted on the shaft 14. The gear 16^a meshes with a pinion 17, the latter being fixed to a gear 17^a, the pinion 17 and gear 17^a being loosely mounted on the shaft 15. The gear 17^a is driven by a pinion 18, which is preferably mounted loosely on the shaft of a motor 19, and is driven therefrom through a friction drive 20 which will transmit the amount of power required to operate the crate actuating bars 5 but will slip and thus avoid injury to the machine should it jam because of a defective crate or from some other cause. The motor, operating through the reduction gearing described, rocks the arm 10^a about its pivot, thus causing regular reciprocatory movements of the crate-advancing bars 5.

Mechanism is provided which is capable of operating positively and with certainty to set the dogs in operative or crate-engaging position, preparatory to each forward or crate-advancing movement of the bars 5, and for reversing the dogs so as to clear the crates preparatory to or at the commencement of each return stroke of the bars 5. The mechanism for reversing the dogs so as to clear the crates preparatory to or at the commencement of the return stroke of the bars 5 may be substantially like that shown and described in my prior application above-referred to. For example, a rock shaft 21 may be suitably mounted in bearings 22

formed in or supported by the upper part of the frame of the machine, this rock shaft carrying a pair of arms 23, the lower ends of which are arranged to swing to-and-fro, 5 in line with the ends of the respective dog-setting bars 5, the lower ends of this bar 23 may be provided with set screws 24 for adjustment purposes, a crank 25 is fixed to the rock shaft 21, and this crank is connected 10 by a rod 26 to a lever 27, the latter being pivoted at 28 on a suitable bracket fixed to a relatively stationary part of the machine, the lever 27 being rocked at the proper times and to the proper degree by a projection 29 formed on a cam 30. The cam 30 is fixed to the cam shaft 31, which latter is driven continuously by the one-to-one ratio gearing 32 driven from the shaft 14, so that the cam shaft makes one complete revolution to each 15 to-and-fro reciprocation of the crate-advancing bars 5. The cam 30 is so set on the cam shaft and the cam projection 29 is so shaped that immediately after the crate-advancing bars 5 commence their return 20 movement from the position shown in Figure 4, the rock shaft 21 will be rotated to swing the arms 23 into engagement with the ends of the respective dog-controlling bars 5, and when these bars 5 have receded to an 25 extent sufficient to enable the dogs 6 to clear the corners of the crates resting on the rails 3, the arms 23 are quickly swung toward the right, from the position shown in Figure 4 to the position shown in Figure 5, the lower 30 ends of the arms 23 moving at a speed greater than the speed of the bars 5, in consequence of which the dog-controlling bars 8 will be shifted toward the right, relatively to the bars 5 and the dogs will be 35 swung outwardly into crate-clearing position. Any suitable means, such for example, as a weight 33 connected to the crank 25, may be used to hold the roller or cam follower 34 on the lever 27 in contact with the periphery of the cam 30.

When the bars 5 reach the limit of their return stroke, it becomes necessary to again actuate the dogs 6 so that they will assume 40 positions to engage the rear sides of the row of crates. The present invention provides improved means operative from the same cam 30 for the setting of the dogs in operative position, when the bars 5 reach the limit of their return movement, whereby 45 the dogs are swung quickly and with certainty into operative position. The improved mechanism just described comprises in the present instance a pair of rods 35 which are pivotally connected to the respective arms 23 and the upper ends of a pair of rockers 36, the latter being pivoted intermediately, at 37, to brackets 38, which latter are bolted or otherwise fixed to a relatively stationary part of the machine. A 50 pair of bars 39 are pivotally connected, at 40,

to the respective rockers 36, these bars being of sufficient length to partly overlie the dog-setting bars 8. The bars 8 are adapted to slide or reciprocate beneath the overlying free ends of the bars 39 and means 70 is provided by which the bars 39 may operate to reverse the position of the bars 8 and to thus set the dogs in operative position, after the crate-advancing bars or members 5 have reached the limit of their return movement. Preferably and as shown in the present instance, each dog-setting bar 8 has a pair of blocks or abutments 41 and 42 secured on its upper side and in longitudinally spaced relation, a pair of rails 43 80 are secured to the tops of these blocks, they being spaced laterally to provide a slot 44 between them, and the free end of each bar 39 is provided with a hooked end 45 which is adapted to project downwardly through 85 and to work freely in the slot 44, a pin 46 being preferably provided on the free end of each bar 39 below the rails 43, for the purpose of retaining the hooked end 45 of each bar 39 in working position beneath the rails 43. During the to-and-fro reciprocations of the bars 5 and 8, the bars 39 may 90 rest on the blocks 41 and slide freely thereon. The blocks 42 are so located as to clear the hooked end 45 of each bar 39 when the 95 bars 8 reach the limit of their left-hand movement, as is shown in Figure 4, but the blocks 41 are so located on the bars 8 that when the crate-advancing bars 5 reach the limit of their return movement, the hooked ends 45 on the bars 39 will engage or 100 will be immediately adjacent to the blocks 41, as is shown by the dotted lines in Figure 6, so that movement of the bars 39 toward the left in Figure 6 will cause the hooked ends 45 of these bars to immediately engage the blocks 41 and to shift the respective bars 8 toward the left or into the full line position shown in Figure 6, the dogs 6 being thereby 105 swung inwardly or into the crate-engaging 110 position shown in Figures 1 and 1^a. The movement of the bars 39 to the proper extent and at the proper time to thus set the dogs in operative position is accomplished 115 by the rockers 36 and rods 35 which receive motion from the arms 23 and the motion of the arms 23 at the proper time and to the proper extent to perform this operation is produced by the projection 47 on the cam 30, this projection being suitably shaped and 120 appropriately located relatively to the projection 29 thereon.

The mode of operation of the crate-feeding mechanism as herein shown and described, is briefly as follows: Assuming the 125 crate-advancing bars 5 to have a regular to-and-fro reciprocatory movement and that a row of crates has been fully advanced along the rails 3 by a full stroke of the crate-feeding bars 5, thus bringing the parts into the 130

position shown in Figure 4, the next operation involves the commencement of the return stroke of the bars 4 and the setting of the dogs 6 to clear the crates during the first 5 part of the return stroke of the bars 5. When the bars 5 reach the limit of their forward or crate-advancing stroke, the left-hand ends (Fig. 4) of the bars 8 will be in engagement with or immediately adjacent 10 to the set screws 24 on the lower ends of the arms 23, and the roller or cam follower 34 will occupy substantially the position shown in Figure 7, relatively to the projection 29 on the cam 30. As the bars 5 and 8 commence their return stroke, the concurrent rotation of the cam 30 in the direction indicated by the arrow, (Fig. 7) will cause the projection 29 on the cam to displace the roller 34, in consequence of which the arms 20 23 will swing toward the right in Figure 4, and when the dogs have been retracted sufficiently with respect to the rear sides of the crates, the cam projection 29 imparts to the arms 23 a motion which is more rapid than 25 the return motion of the bars 5 and 8, as the result of which the bars 8 are shifted toward the right relatively to the bars 5. from the position shown in Figure 5, the dogs being 30 thereby swung outwardly into inoperative or crate-clearing position. The bars 5 continue their return stroke with the dogs occupying such inoperative or crate-clearing position, but when the return stroke of these parts is completed, the hooked ends 45 on 35 the bars 39 will engage or will be immediately adjacent to the blocks 41 on the bars 8 and at this moment, and preferably before the forward or working stroke of the bars 5 commences, the bars 39 are drawn suddenly 40 to the left, from the dotted line position to the full line position shown in Figure 6, this motion of the bars 39 being derived from the arms 23 through the rockers 36 and rods 35, and the arms 23 receiving their motion for 45 the performance of this operation from the projection 47 on the cam 30 which engages the roller or cam follower 34 and displaces it at this moment in substantially the manner shown in Figures 2 and 3. The dogs 6 are thereby set quickly and positively into 50 operative or crate-advancing position before the commencement of the working stroke of the crate-advancing bars 5. It will be understood that the swinging movement of the arms 23 under the action of the cam projection 29, which takes place at the commencement of the return stroke of the bars 5, causes a merely idle operation of the bars 39, as the hooked ends 45 of these bars, at 55 that time, are not in operative relation with the blocks or abutments 41.

From the foregoing, it will be understood that means is provided which is operated by the same cam to not only set the crate-advancing dogs in inoperative or crate-clear-

ing position at the commencement of the return stroke of the crate-advancing means, but which is also operative to set the dogs in operative or crate-engaging position after the return stroke of the crate-advancing means has been substantially completed, at which time the crate-advancing means is stationary or substantially so, and the pairs of dogs occupy positions at substantially the maximum distances in rear of the respective crates. Consequently, the amount of clearance provided between the pivotal centers of the dogs and the rear corners of the respective crates is at or near the maximum, and hence the dogs can be made of greater length 80 than would be practicable if the dogs were set during any considerable movement of the crate-advancing means, thus insuring increased area of contact between the dogs and the crates, and thereby avoiding danger of 85 injuring the crates which are usually constructed of wood; and, moreover, greater regularity and smoothness in operation results from the performance of both dog-setting operations from the same cam. 90

I claim as my invention:—

1. Crate-advancing means comprising, in combination, a reciprocatory member carrying a dog movable relatively to it, a dog setting element movable with said member, a pair of actuating devices movable in reverse directions relatively to each other and with respect to which said element is movable during the reciprocating movements of said member to bring said element successively into operative position to be engaged by one of said devices when said member is substantially at the commencement of its crate-advancing stroke and into position to be engaged by the other of said devices when said member is substantially at the commencement of its return stroke, and means for actuating said devices to set the dog respectively in crate-engaging and crate-clearing positions. 100

2. Crate-advancing means comprising, in combination, a reciprocatory member carrying a dog movable relatively to it, an abutment connected to and movable in unison with the dog, a bar arranged to ride on said abutment during the reciprocating movement of said member and having an operating part to which said abutment is presented when said member is substantially at the commencement of its crate-actuating stroke, and means for actuating said bar to shift said abutment and thereby set the dog in crate-engaging position. 115

3. Crate-advancing means comprising, in combination, a reciprocatory member carrying dogs movable relatively to it, a dog-setting bar connected to the dogs and movable with said member, a guide carried by said bar and having an abutment toward one end, an actuating bar having an end co- 120 125 130

operating with said guide and arranged to be engaged by said abutment when said member is toward the commencement of its crate-advancing stroke, and means for actuating said bar to displace said abutment relatively to said member and to thus set the dogs in crate-engaging position.

4. Crate-advancing means comprising, in combination, a reciprocatory member carrying dogs movable relatively to it, driving means for reciprocating said member, a dog setting element reciprocatory with said member, a pair of actuating devices connected to move in reverse directions relatively to each other and with respect to which said element is movable to bring it into operative position relatively to the respective actuating devices to set the dogs in operative crate-engaging position preparatory to the crate-advancing stroke of said member and to set the dogs in inoperative crate-clearing position substantially at the commencement of the return stroke of said member, and means driven in timed relation with said driving means for operating said devices.

5. Crate-advancing means comprising, in combination, a reciprocatory member carrying dogs movable relatively to it, driving means for reciprocating said member, dog-setting mechanism, and a pair of actuating elements driven in reverse directions relatively to each other and in timed relation with said driving means for actuating said dog-setting mechanism to set the dogs in operative crate-engaging position when said member is substantially at the commencement of its crate-advancing stroke and for subsequently actuating said mechanism to set the dogs in inoperative position when said member is substantially at the commencement of its return stroke.

6. Crate-advancing means comprising, in combination, a reciprocatory member carrying dogs movable relatively to it, a cooperative dog-setting element, a pair of actuating elements connected to move in reverse directions relatively to each other, and means operative in timed relation with the strokes of said member to actuate said actuating elements while said member is at the commencement of its advancing stroke to cause one of said actuating elements to operate on the dog setting element and thus set the dogs in operative position and to subsequently actuate said actuating elements while said member is substantially at the commencement of its return stroke to cause

the other of said actuating elements to operate on the dog-setting element and thus set the dogs in inoperative position.

7. In crate-advancing means comprising a reciprocatory member carrying dogs movable relatively to it, and a dog setting element reciprocable with and movable relatively to said member, a pair of actuating elements connected to move in reverse directions relatively to each other to actuate the dog-setting element to respectively set the dogs in operative position when said member is substantially at the commencement of one of its strokes and to set the dogs in inoperative position when said member is substantially at the commencement of its other stroke.

8. Crate-advancing means comprising a reciprocatory member carrying dogs movable relatively to it, a dog setting bar operatively connected to the dogs and reciprocable with said member, a reciprocatory arm adapted to engage said dog-setting bar when said member is substantially at the commencement of one of its strokes and to set the dogs in inoperative position, a bar connected to said arm to move in reverse direction therewith and adapted to engage the dog-setting bar when said member is substantially at the commencement of its other stroke and to set the dogs in operative crate-engaging position, and means for actuating said arm successively and in timed relation with said reciprocatory member.

9. Crate-advancing means comprising a reciprocatory member carrying dogs movable relatively to it, a dog-setting bar reciprocal with said member, an arm adapted to swing into engagement with the dog-setting bar when said member is substantially at the commencement of one of its strokes to set the dogs in inoperative position, an actuating bar, a rocking lever connecting said actuating bar to said arm and operative to reciprocate said actuating bar in a reverse direction to the direction of movement of said arm and to cause said actuating bar to engage the dog-setting bar when said member is substantially at the commencement of its other stroke and thereby set the dogs in operative crate-engaging position, and means including a cam which is shaped to impart successive movements to said arm in timed relation with the reciprocations of said member.

In testimony whereof I have hereunto set my hand.

WILLIAM W. BIRNSTOCK.
